UNITED STATES PATENT OFFICE.

ADDIE E. CARDENZO, OF WASHINGTON, DISTRICT OF COLUMBIA.

TOY PLAYGROUND.

1,185,176.

Specification of Letters Patent.

Patented May 30, 1916.

Application filed January 20, 1916. Serial No. 73,114.

To all whom it may concern:

Be it known that I, ADDIE E. CARDENZO, a citizen of the United States, residing at Washington, District of Columbia, have invented certain new and useful Improvements in Toy Playgrounds, of which the following is a specification.

This invention relates to toys and has special relation to the toy simulation of a children's playground.

More particularly the invention relates to a toy playground made up of knock-down or separable sections so arranged and marked that the device may be readily set up or assembled, the several parts being provided with corresponding characters at their points of junction so that the child using the toy can, by coördinating parts having like marks, properly assemble the device 20 with all of the parts in their proper relationship and thereby erect the different apparatus used in such a playground at the appropriate points.

One principal object of the invention is to provide an improved toy simulation of a playground wherein knock down parts are so arranged as to be quickly assembled on a base, the latter being provided with means for holding dolls or images in proper position in relation to the various apparatus disclosed.

A second principal object of the invention is to provide such distinction in the assembling indications and arrangements that no 25 two of the apparatus set up will interfere in operation with each other.

With the above and other objects in view, as will be hereinafter apparent, the invention consists in general of certain novel arrangements of details and combinations of parts hereinafter fully described, illustrated in the accompanying drawings and set forth as claimed.

In the accompanying drawings like characters of reference indicate like parts in the several views, and Figure 1 is a perspective view of a toy playground constructed in accordance with this invention. Fig. 2 is a perspective view of a portion of the fence used as constructed in accordance herewith. Fig. 3 is a transverse section through the fence on line III—III of Fig. 1. Fig. 4 shows the corner joint of a portion of a supporting frame for certain of the apparatus. Fig. 5 shows the foot connection for the swings in the playground. Fig. 6 is a

section showing the manner of doweling the two parts of the base together; and Fig. 7 is a section showing one of the loops used to engage a foot of a doll or image to hold the 60 doll or image in proper position near a piece of apparatus.

In carrying out the objects of the invention and in the embodiment herein illustrated, which is to be taken only as illustrating one of the different embodiments coming within the scope claimed, it is preferred to make the base in two or more sections 10, 10' which are detachably connected by alining means 11 here illustrated as 70 dowels.

The fence, which surrounds the entire base consists of sections each having spaced stringers or rails 12 and pickets 13. These sections are detachably connected at the corners by dowels 14, fitting dowel holes 15, and depending from the bottom rail 12 are dowels 16 which fit suitable holes in the base so that, when the fence is assembled, the parts of the base are locked together by the 75 coöperation of the transverse fence sections with such base. A gate 17 is preferably provided in one of the fence sections to assist in the simulation of an actual playground.

Located at various points within the fence 80 are different forms of playground apparatus such as the tennis court 18, merry-go-rounds 19 and 19', swings 20, sand box 21, see-saws 22, slide or chute-the-chute 23, frame 24 for flying rings 24^a, trapeze 24^b and ladders 24^c, 90 and tether ball 25. The ends of the supports of frame 24, carrying the trapeze 24^a and flying rings 24^b are held together by dowel pins 24^c and 24^d, fitting in corresponding holes of the other parts, as shown in Fig. 4. 95 Of course, the particular number and arrangement of these various pieces of apparatus may be varied at will, but in each instance the supports are doweled removably into the base and where joints occur these 100 are preferably connected by dowels as shown in Fig. 4.

Adjacent each dowel the part carrying the dowel has impressed on or marked in any manner thereon a figure or character 26, 105 while the part coöperating with the dowel carrying part is provided with a suitable dowel hole adjacent which is likewise impressed or marked with a duplicate figure or character 27, so that by mating the parts 110 bearing the same characters the different parts may be quickly assembled without

danger of fitting the parts together in the wrong way.

In order to properly support the dolls or images 28, on the base sections 10, 10', said sections are provided at appropriate places on or adjacent the various apparatus with loops 29, made of wire or other suitable material, which receive the toe portion of one of the doll's feet and thereby prevent the doll from falling over.

From the foregoing it will be plain that there has been provided an improved toy of this description which can be readily set up for play or taken down for storage and 15 packing.

What is claimed is:—

1. In a toy playground, a base having a plurality of sections, means to connect the

sections in proper relation, and a fence consisting of interconnected sections, certain of 20 said fence sections having connection with a plurality of base sections to lock the base sections against accidental separation.

2. In a toy playground, a base, a series of 25 playground apparatus detachably mounted on the base, and loops to receive and hold a portion of a doll's foot mounted on the base in coöperative position to the various apparatus.

In testimony whereof I affix my signature 30 in the presence of two witnesses.

ADDIE E. CARDOZO.
